UNITED STATES PATENT OFFICE.

JOHN E. JEFFORDS, OF PHILADELPHIA, PENNSYLVANIA.

DESIGN FOR A TEA-POT.

SPECIFICATION forming part of Design No. 19,256, dated August 6, 1889.

Application filed July 12, 1889. Serial No. 317,333. Term of patent 7 years.

To all whom it may concern:

Be it known that I, JOHN E. JEFFORDS, a citizen of the United States, resident of Philadelphia, in the county of Philadelphia and State of Pennsylvania, have invented a certain new and useful Design for Tea-Pots; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a side view. Fig. 2 is a top view with the cover raised.

This design has relation to tea-pots; and it consists in the novel form and combination of the parts thereof, as shown and described.

In the accompanying drawings I have illustrated my design, which consists of a slightly-flattened circular bowl, the form of which is that of an oblate spheroid, the base having a circular bead *b* and the top a circular bead *c*, of slightly less diameter than the bead *b*, rising therefrom, and having an interior circular concave marginal lip *d* around the opening *e*. The bead *b* springs from the sides of the rear lug *g*, which is rounded at its upper end and joins the convex wall of the bowl by its vertical rear face *h* just above the junction of the upper arm *k* of the handle *l*, which extends upward and

rearward in wave-like form to the leaf crest 35 *m*, which is at a higher level than the top of the lug *g*. Thence the handle is curved outward and downward, and finally downward and inward on a line tangent to the lower portions of the bowl just above the base-bead 40 *b*. Horizontally around the bowl extends the equatorial rise or rib projection which joins the general convex wall of the bowl above, and below by slightly concave annular surfaces, as indicated at *n n*. 45

The spout is of delicate curvature, joining the bowl by a broad convex breast *v* in front of its equatorial portion, as shown.

The lid *z*, of flattened convex form, is provided with a hinge-lug *s*, having the rounded 50 oblique upstanding rear flange *t*.

What I claim as my design, and desire to secure by Letters Patent, is—

The design for a tea-pot herein shown and described, the same comprising the oblate 55 spheroid bowl having the equatorial rib, the upper and lower circular beads, the curved hinge-lug rising from the upper bead, and the tangential curved handle having the leaf crest above the level of said hinge-lug, as set 60 forth.

In testimony whereof I affix my signature in presence of two witnesses.

JOHN E. JEFFORDS.
